Primary Examiner—Wallace R. Burke*Assistant Examiner*—H. Bayham*Attorney, Agent, or Firm*—David O'Reilly**[57] CLAIM**

The ornamental design for a kite line spool for a portable power drive, as shown and described.

DESCRIPTION

FIG. 1 is a front perspective view of a kite line spool for a portable power drive showing my new design; and, FIG. 2 is a rear perspective view thereof.

The phantom lines showing a portable power drive and a string in FIG. 1 are for illustrative purposes only and form no part of the claimed design.

Fig. 1.

Fig. 2.
